UNITED STATES PATENT OFFICE.

PHILLIP HIEN, OF CHICAGO, ILLINOIS.

DRAFT-GEAR AND BUFFING APPARATUS.

SPECIFICATION forming part of Letters Patent No. 715,068, dated December 2, 1902.

Application filed July 28, 1902. Serial No. 117,244. (No model.)

To all whom it may concern:

Be it known that I, PHILLIP HIEN, a citizen of the United States, residing at Chicago, county of Cook, State of Illinois, have invented a certain new and useful Improvement in Draft-Gear and Buffing Apparatus; and I declare the following to be a full, clear, and exact description of the invention, such as will enable others skilled in the art to which it pertains to make and use the same, reference being had to the accompanying drawings, which form a part of this specification.

My invention relates in general to apparatus for yieldingly resisting a strain or gradually absorbing a shock, and more particularly to a draw-gear and buffing apparatus for gradually transmitting to the draft-timbers of a car the sudden pull or push exerted upon the draw-bar in starting and stopping a train.

20 A comparatively limited relative movement between the draw-bar and draft-timbers of a car is permitted, and in order that the sudden shocks in pulling and buffing may be absorbed or gradually transmitted from the 25 coupler to the car-frame it is necessary that apparatus should be interposed between the draw-bar and draft-timbers of a car capable of exerting a great resistance while its members are being relatively moved the available 30 longitudinal distance. Heretofore apparatus for the purpose mentioned has comprised springs or friction-surfaces or a combination of springs and friction-surfaces, the arrangement being such that a sudden pull or push 35 upon the draw-bar is dissipated or gradually communicated to the draft-timbers of a car through compressing interposed springs or relatively moving the friction devices. In order to secure a combined spring and frictional resistance, it has previously been necessary, so far as I am aware, to employ frictional devices separate from and in addition to a spring or springs.

The primary object of my invention is to 45 provide in an apparatus of the same general character as that described and claimed in my pending application, Serial No. 116,187, filed July 19, 1902, for transforming a sudden relative movement between adjacent 50 parts to a gradual movement, a telescopic radially-rigid interior core, around which are supported a plurality of elements capable

when subjected to compression of individually exerting a gradually-yielding spring resistance and simultaneously generating a frictional resistance. 55

A further object of my invention is to provide in an apparatus of the character disclosed in my copending application, above referred to, a telescopic radially-rigid interior 60 core around which are supported a series of resilient elements capable of first exerting a torsional resistance when subjected to compression and subsequently exerting a combined frictional and spring resistance by the 65 relative movement between adjacent elements.

A further object of my invention is to provide an apparatus of the character referred to which will be simple in construction, inexpensive in manufacture, and efficient in operation. 70

The embodiment of my invention herein disclosed consists, generally described in an interior telescopic radially-rigid core, around 75 which are supported expandable and compressible spring-rings having inclined engaging friction-surfaces, the core and spring-rings being interposed between followers upon which the strain is exerted or the blow 80 is received and by which the same is communicated to the friction-rings, and thereby through the relative movement of the rings gradually absorbing the strain or dissipating the blow, owing to the combined spring and 85 frictional resistance due to the tension imparted to the spring-rings and to the engagement between their friction-surfaces.

My invention will be more fully described hereinafter with reference to the accompanying drawings, in which the same is illustrated as embodied in a convenient and practical form, and in which— 90

Figure 1 is a plan view thereof; Fig. 2, a central sectional view on line 2 2, Fig. 1; Fig. 95 3, a view similar to Fig. 2, showing the positions of the parts when the apparatus has been subjected to compression; Fig. 4, an elevational view of the central part of the interior core, and Fig. 5 an elevational view of one of 100 the end portions of the interior core.

Similar reference characters are used in the several figures of the drawings to designate similar parts.

Reference characters A' and A² indicate followers, which support a radially-rigid telescopic core and between which are interposed frictional spring-rings, the latter surrounding 5 and being supported by the core. The follower A' is provided with a hollow cylindrical projection A³, which fits within a circular flange D³ of the adjacent end portion D' of the telescopic core. The follower A² is provided 10 with a hollow cylindrical portion A⁴, similar to the portion A³ on the follower A' and projecting toward the same. A circular flange D⁴, forming part of the other end portion D² of the core, surrounds the projection A⁴ on 15 the follower A². The central part E of the core is provided with circular flanges extending in opposite directions, one of which, E³, surrounds the flange D⁵ on the end portion D' of the core, while the other, E⁴, surrounds a 20 circular flange D⁶, projecting from the other end portion D² of the core. The central part of the core is provided with a radially-projecting flange E'. A longitudinal rib e' is fixed to the inner surface of the central part E of 25 the core, the opposite ends of which respectively engage notches formed in the adjacent circular flanges of the end parts D' and D² of the core. For instance, the end e⁵ of the rib projects into the notch d⁵, formed in the flange 30 D⁶, while the end e⁶ of the rib e' projects into the notch d⁶, formed in the flange D⁶. A rib d³ is secured to the inner surface of the flange D³ of the part D' of the core and extends in alinement with the notch d⁵. The rib d³ engages 35 a slot a³, formed in the cylindrical projection A³ on the follower A'. A key d⁴ is fixed to the inner surface of the flange D⁴ on the part D² of the core and extends within a recess a⁴, formed in the cylindrical portion A⁴ 40 of the follower A². The keys e', d³, and d⁴ are located in longitudinal alinement, as are also, consequently, the slots d⁵, d⁶, a³, and a⁴. The keys and slots prevent the parts of the core and the followers from rotating relatively, 45 but permit a telescopic movement between the parts of the core and followers, owing to sufficient space being left between the opposed vertical surfaces of the adjacent parts.

A compressible spring-ring C' surrounds the 50 circular flange D³, the opposite ends of the ring being separated by a stop d (see Fig. 5) on the exterior of the flange D³. A similar open compressible ring C² surrounds the circular flange D⁴ on the opposite end portion 55 D² of the core, a stop d on the exterior of the flange D⁴ being located between the ends of the ring. Another compressible open ring C³ surrounds the cylindrical flange E³ of the central portion E of the core, a stop e³, formed 60 on the exterior of the flange, being interposed between the ends of the ring. An open compressible ring C⁴, similar to the ring C³, surrounds the circular flange E⁴ of the central part E of the core, the ends thereof being 65 separated by a stop e⁴ on the exterior of the flange E⁴. The rings C' and C³ are provided with frictional surfaces inclined in the same

direction, the inclination of the former, however, being less with respect to a horizontal line than is the inclination of the latter. The 70 rings C² and C⁴ have frictional surfaces inclined in the same direction, the inclination of the former being the same as the inclination of the friction-surface on the ring C', but less than the inclination of the surface 75 on the rings C³ and C⁴. The inclination of the surface of the ring C⁴ is less than that of the surfaces c² and c⁴ on the rings C' and C², but is the same as that of the surface c³ on the ring C³. An expansible open ring B' surrounds the ring C' and is provided with a friction-surface b', having the same angle of 80 inclination as the surface c' on the ring C'. A circular flange a', fixed to the follower A', extends within the ring B' and is adapted to engage the adjacent inclined surface thereof. An expansible open spring-ring B² surrounds the compressible ring C² and is provided with an inclined surface b², adapted to engage the surface c² on the ring C². A circular flange 85 a² projects from the follower A² within the spring-ring B², the adjacent surfaces of the flange a² and the ring B² being inclined, as indicated in Figs. 2 and 3. Stops a⁵ and a⁶, 90 fixed to the followers A' and A², respectively, extend between the ends of the respective rings B' and B². An expansible open ring B³ surrounds the compressible ring C³ and is provided with an inclined friction-surface b³, adapted to engage the surface c³ on the ring 95 C³. The ring B³ also surrounds the end portion D' of the core, said portion of the core and the ring B³ being provided with inclined coöperating surfaces. A stop d⁷ projects from the inclined exterior surface of the part D' 100 of the core and extends between the ends of the ring B³. An expansible ring B⁴, similar to the ring B³, surrounds the compressible ring C⁴ and is provided with an inclined frictional surface b⁴, adapted to engage with the 105 inclined surface c⁴ on the compressible ring C⁴. The ring B⁴ is also provided with an inclined surface which engages a correspondingly-inclined surface d², formed on the end portion D² of the core. A stop d⁸, fixed to 110 the portion D² of the core, projects between the ends of the ring B⁴. The stops a⁵ and d⁸ extend in the same direction, while the stops d⁷ and a⁶ preferably extend in an opposite direction, so that the openings in the adjacent rings are staggered. The stops for the 115 compressible rings are also located one hundred and eighty degrees from each other and ninety degrees from the stops for the expansible rings, thereby causing the openings in the adjacent compressible rings to be also 120 staggered. Both the compressible and expansible rings are preferably slightly spirally disposed, as indicated in the figures. The inclined surfaces of the end expansible rings 125 which engage the end compressible rings are preferably inclined at a more acute angle to the horizontal than are the inclined surfaces on the the central expansible rings which en- 130

gage the inclined surfaces on the central compressible ring.

The operation of the embodiment of my invention above described is as follows:

- 5 When the followers A' and A² are moved together, due, for instance, to the relative movement between a draw-bar and the draft-timbers of a car, the rings are forced together and the camber or slight spiral twist removed.
- 10 A continuation of the movement of the followers toward each other compresses the end compressible rings C' and C², through the engagement between the inclined surfaces c' and c² with the inclined surfaces b' and b² on the end expandible rings. The end expandible rings B' and B² are then expanded until they engage the central expandible rings B³ and B⁴. The expandible rings B³ and B⁴ are consequently moved toward the radial flange 15 E' of the central part E of the core and compress the central compressible rings C³ and C⁴ through the engaged frictional surfaces c³, c⁴, b³, and b⁴, respectively. When the rings C³ and C⁴ have been compressed, a continuation 20 of the movement of the followers toward each other causes the central expandible rings B³ and B⁴ to be expanded until they engage the radial flange E', and during such expansion of the rings B³ and B⁴ the 25 expandible rings B' and B² are further expanded. It is therefore evident that a resistance is first afforded by the camber or spiral twist of the rings, and such resistance may be sufficient to absorb the strain occurring 30 ring during the ordinary running of a train, so that the expansion and contraction of the rings and the consequent frictional resistance are only brought into action when a sudden or violent shock occurs, as in the 35 starting or stopping of the train. When a sufficient force is exerted upon the followers, the end inner rings afford spring resistance and also frictional resistance through the relative movement between their inclined 40 surfaces with the inclined surfaces on the end expandible rings. Subsequently the end expandible rings are expanded and forced into engagement with the central expandible rings, whereupon the retardation is produced 45 by the compression of the central compressible rings and the expansion of the central expandible rings and the friction generated by the relative movement between the inclined engaging surfaces. The telescopic connections 50 between the followers and the parts of the core permit the followers to approach each other sufficiently to bring into action in the serial manner above described the several pairs of compressible and expandible 55 rings.

In the operation of the embodiment of my invention herein disclosed frictional resistance is not merely generated by the relative movement of the engaging inclined surfaces on adjacent rings, but friction is also generated during the compression of the inner rings by the relative movement of the surfaces thereon

which engage the radial surfaces on the core. In other words, when the inner rings are compressed from the position shown in Fig. 2 to that shown in Fig. 3 the surface on each ring which engages the corresponding surface on the radial projections surrounding the sections of the core creates a frictional resistance. When the force which has moved the followers together is discontinued, the tension of the rings effects the return of the parts to their normal positions through the engaged inclined surfaces.

It is apparent that my invention is adapted for a variety of uses in addition to that of serving as a draw-bar and buffing apparatus, and while I have described more or less precisely the details of construction I do not wish to be understood as limiting myself thereto, as I contemplate changes in form, the proportion of parts, and the substitution of equivalents as circumstances may suggest or render expedient without departing from the spirit of my invention.

I do not claim the invention herein disclosed generically, inasmuch as the generic invention common to this application and to my prior application, Serial No. 116,187, previously referred to, is claimed in said prior application; but I do claim in this application only the features of construction not disclosed in my said prior application.

Having now fully described my invention, what I claim as new, and desire to secure by Letters Patent, is—

1. In a device of the character described, the combination with a series of resilient elements having inclined frictional surfaces, of a telescopic core surrounded by and supporting said elements whereby when said series of elements are subjected to compression they are relatively moved and thereby placed under tension.

2. In a device of the character described, the combination with followers, of a telescopic core supported by said followers, a series of resilient elements having inclined frictional surfaces interposed between said followers and surrounding said core.

3. In a device of the character described, the combination with a series of resilient elements of graduated resisting capacity having inclined frictional surfaces, of a telescopic core surrounded by and supporting said elements.

4. In a device of the character described, the combination with a series of resilient rings having inclined frictional surfaces, of a telescopic core surrounded by and supporting said rings.

5. In a device of the character described, the combination with an expandible resilient ring, of a compressible resilient ring, said rings having inclined engaging frictional surfaces, and a core surrounded by and supporting said rings.

6. In a device of the character described, the combination with followers, of a telescopic core supported by said followers, a series of

expansile resilient rings having inclined frictional surfaces, and compressible resilient rings surrounding said core and supported thereby and having inclined frictional surfaces engaging the frictional surfaces of the expansile rings.

7. In a device of the character described, the combination with followers, of a telescopic core supported by said followers, a series of 10 spirally-disposed expansile resilient rings having inclined frictional surfaces, and a series of spirally-disposed compressible resilient rings surrounded and supported by said core and engaging the inclined frictional surfaces on the expansile rings.

8. In a device of the character described, the combination with followers, of a telescopic core supported by said followers, of a series 20 of expansile rings of graduated resisting capacity having inclined frictional surfaces, and a series of compressible resilient rings of graduated resisting capacity having inclined frictional surfaces engaging the frictional surfaces of the expansile rings.

25 9. In a device of the character described, the combination with followers, of a telescopic core supported by said followers, of a series of resilient elements having inclined frictional surfaces the angle of inclination of the 30 surfaces being graduated whereby when said followers are subjected to compression the engagement between the inclined frictional surfaces of the elements serially places the same under tension.

35 10. In a device of the character described, the combination with followers, of a core comprising a plurality of parts longitudinally movable with respect to each other the end parts being supported by and movable longitudinally with respect to said followers, a series 40 of resilient elements having engaged inclined frictional surfaces interposed between said followers and surrounding said core.

11. In a device of the character described, 45 the combination with followers having cylindrical portions projecting toward each other, of a core comprising end portions surrounding and supported by the projections on said followers, and an intermediate portion surrounding 50 projections on and supported by said end portions, means for preventing relative rotary movement between said followers and said core and also between the parts of said core, and a series of resilient elements 55 having engaged inclined frictional surfaces interposed between said followers and surrounding said core.

12. In a device of the character described,

the combination with a series of resilient elements, of a series of non-resilient elements 60 supported adjacent to said resilient elements, said resilient and non-resilient elements having engaging frictional surfaces at an angle to the axis of the resilient elements whereby when said resilient elements are flexed the 65 said frictional surfaces thereon are moved relatively to the engaged frictional surfaces on said non-resilient elements.

13. In a device of the character described, the combination with a series of compressible 70 spring-rings, of a series of non-resilient elements supported adjacent to said rings, said rings and non-resilient elements having engaging frictional surfaces whereby when said rings are compressed the frictional surfaces 75 thereon are moved relatively to the engaged frictional surfaces on said non-resilient elements.

14. In a device of the character described, the combination with a series of resilient elements, of a series of non-resilient elements supported adjacent to said resilient elements, and a core surrounded by and supporting said elements, said resilient and non-resilient elements having engaging frictional surfaces 80 85 whereby when said resilient elements are flexed the said frictional surfaces thereon are moved relatively to the engaged frictional surfaces on said non-resilient elements.

15. In a device of the character described, 90 the combination with a series of compressible spring-rings, of a series of plates supported adjacent to said spring-rings, and a core surrounded by and supporting said compressible rings and said plates, said rings having frictional surfaces adapted to engage and to be moved relatively to said plates when compressed. 95

16. In a device of the character described, the combination with a series of expansile 100 spring-rings having inclined frictional surfaces, of a series of compressible spring-rings having inclined frictional surfaces engaging the inclined frictional surfaces of the expansile rings, a core surrounded by and supporting said compressible rings, and plates carried by said core, said compressible rings having frictional surfaces adapted to engage and move relatively to said plates when the rings are compressed. 105 110

In testimony whereof I sign this specification in the presence of two witnesses.

PHILLIP HIEN.
